UNITED STATES PATENT OFFICE.

LEVI R. SAMPLE, OF MARSEILLES, ASSIGNOR OF ONE-HALF TO JOSHUA SMITH, OF CHICAGO, ILLINOIS.

FOLDING IRONING-TABLE.

SPECIFICATION forming part of Letters Patent No. 282,469, dated July 31, 1883.

Application filed September 27, 1882. (No model.)

To all whom it may concern:

Be it known that I, LEVI R. SAMPLE, of Marseilles, county of La Salle, and State of Illinois, have invented certain new and useful Improvements in a Folding Ironing-Table, of which the following is a full, clear, and exact description, that will enable others to make and use the same, reference being had to the accompanying drawings, and to letters 10 of reference marked thereon, forming a part of this specification.

This invention relates to improvements in that class of ironing boards or tables that are adapted to be adjusted to different positions, and when not required for use may be conveniently folded up in a compact form.

Figure 1 is a view in perspective embodying my improvement; Fig. 2, a vertical central longitudinal section; and Fig. 3, a transverse section in the plane 3 3, Fig. 2.

Referring to the drawings, A represents the table or ironing-board proper, having the front end rounded off, the back end being square, and is provided with the sad-iron stand A', rigidly secured to the under side of the same and projecting outward therefrom, as shown in Figs. 1 and 2 of the drawings, so as to leave the top of the table entirely clear. The table is supported by the long legs B B', the short legs C C', and the adjustable support D. The upper ends of the longer legs are pivoted to the ends of the cleat a, placed on the under side and located at the back end of the table, the legs extending therefrom at an oblique angle, and resting on the floor at a point under the front end of the table. The lower ends of these legs are connected and braced by the roller a', which is adapted to rotate. The lower end of the broad support D is rigidly secured to the roller a', while the upper end comes in contact with the under side of the table, and may be moved to different positions, for the purpose of varying the height of the table. The loose end of the support D is retained in place at the different points of adjustment by means of the series of cleats a², attached to the under side of the table. This support D may be turned inward and downward when folding up the table, and turned down and outward when a large garment is to be slipped over the table. The upper ends of the shorter legs, C C', are pivoted to the inside

of the legs B B' at a point near the upper ends, and are braced by the rounds a³ a⁴. When the device is folded flat these legs fold up inside 55 of the longer legs. One end of the metallic brace-rods b b' are permanently secured to the inside of the legs B B', while the opposite ends are adjustably connected with the legs C C'. The angular shoulder b² on the brace-rods is 60 adapted to engage with the staple d, inserted in the legs C C'. As the height of the table is lowered the hook end d' may be made to engage with the staple d, whereby the brace-rods are lengthened out to conform to the 65 change of position. By this arrangement the brace-rods may be conveniently shortened or lengthened, as circumstances may require, and, being made of metal, are both light and durable.

d² d³ are light bars which slide in and out from underneath the table, and are for the purpose of holding small articles of clothing.

I am aware that ironing-tables have been provided with inclined legs having an adjustable support for the table attached to a roller journaled in said inclined legs, and that tables have been provided with a support having an angular shoulder which rests on the top of the table-supporting standard, and to these features I make no claim; but I am not aware that brace-rods having a hook at one end and an angular shoulder near the hook has ever been used.

Having thus described my invention, what I claim, and desire to secure by Letters Patent, is—

1. The combination, with an ironing-board having cleats upon its under side, of inclined legs B B', short legs C C', having staples d, 90 adjustable supports D, and adjustable brace-rods b b', provided with angular shoulders b² and the hook end d', substantially as described.

2. An ironing-table having a board, A, provided with extensions A' and d² d³, inclined legs B B', short legs C C', having staples d, 95 adjustable supports D, and adjustable brace-rods b b', provided with angular shoulders b² and the hook end d', substantially as described.

LEVI R. SAMPLE.
